UNITED STATES PATENT OFFICE.

WILLIAM SPARKS, OF JACKSON, MICHIGAN, ASSIGNOR, BY MESNE ASSIGNMENTS, TO STEWART-WARNER SPEEDOMETER CORPORATION, OF RICHMOND, VIRGINIA, A CORPORATION OF VIRGINIA.

LIQUID-FEEDING DEVICE

Application filed July 2, 1921. Serial No. 462,264.

To all whom it may concern:

Be it known that I, WILLIAM SPARKS, of Jackson, in the county of Jackson, in the State of Michigan, have invented new and 5 useful Improvements in Liquid-Feeding Devices, of which the following, taken in connection with the accompanying drawings, is a full, clear, and exact description.

This invention relates to certain improvements in liquid feeding devices for use particularly in supplying liquid fuel to internal combustion engines of automobiles and the like in connection with which it is very often desirable to have the primary fuel tank carried on the vehicle at a level below the carburetor.

The main object of the invention is to provide a device of comparatively simple construction and high efficiency in automatic 20 operation, with particular relation to the construction of the vacuum tank portion thereof, to which the liquid fuel is elevated, as by the suction of the engine, and intermittently discharged therefrom, to be fed by 25 gravity to a vaporizing device, as for instance, to the float chamber of a commercial carburetor.

Another object relates to the construction and operation of the portions of the apparatus by means of which atmospheric pressure and vacuum are alternated in the upper chamber of the vacuum tank, and to the particular construction and method of operation of the valves controlling not only the 35 atmospheric and suction connections, but also the discharge opening between the upper and lower chambers of the tank.

Other objects and advantages relate to the 40 details of construction and operation of the apparatus, all as will more fully appear from the following description, taken in connection with the accompanying drawings, in which:—

Figure 1 is a top plan view of a device of 45 my invention.

Figure 2 is a section on line 2—2, Figure 1.

Figure 3 is an end elevation of the valve 50 and its casing showing a section of the tank.

Figure 4 is a view similar to Figure 3, showing the valve in a different position.

Figure 5 is a side view of the float-actuated lever and its stem.

Figure 6 is a top plan view of the lever of Figure 5.

Figure 7 is a view partially in section of the loose connection between the two parts of the float stem.

Figure 8 is a top plan view of one of the dogs illustrated in Figures 4 and 5.

Figure 9 is a section on line 9—9, Figure 1.

Figure 10 is a horizontal section through the valve casing and the operating structure for the valve.

Figure 11 is a section on line —11—11, Figure 1.

Figure 12 is a section similar to the section shown in Figures 2 and 9 of a somewhat modified form of structure.

The apparatus, as shown in Figures 1 to 11 inclusive, comprises a tank structure, which may be of substantially cylindrical form, closed at its lower and upper ends, except for the connection hereinafter noted, and 75 divided by a partition —1— in two chambers —2— and —3— respectively, the chamber —3— adapted to be maintained under atmospheric pressure at all times, so as to freely feed liquid by gravity through nipple —4— to a carburetor, or other vaporizing device. The chamber —2— is alternately under atmospheric pressure, and vacuum, so that fuel is alternately drawn thereinto and discharged therefrom into the chamber —3—.

For the purpose of automatically effecting this operation, the upper chamber —2— is connected by nipple —5— with any suitable source of liquid fuel supply, such source 90 being usually the ordinary low level tank on an automobile, from which it is necessary to elevate the liquid into the chamber —2—. In order to alternate vacuum and atmospheric pressure in the upper chamber —2—, a float —6— is provided, loosely mounted upon the float stem —7—, such stem rigidly carrying the valve —8— which controls the discharge orifice —9— through the partition —1—. This float stem is, as indicated in Figure 7, formed in two parts, loosely connected together, and having a limited longitudinal relative movement. The upper portion —10— of the stem passes through a disk —11— which has an opening of a size to 100 tightly surround the part —10—, the upper

end of the stem being connected to a hollow piston —12— movable in the substantially cylindrical nipple —13— and spring-pressed upwardly by the spring —14— interposed between the interior of the piston head and the disk —11—, so that normally the spring tends to elevate the piston —12— and thereby raise the valve —8— from its seat.

In order, however, at the required time to close valve —8— and produce vacuum in the chamber —2— a valve casing —15— is provided, which has a passage-way —16— therethrough leading from the pipe —17—, which is in communication with any source of suction, as the manifold of the engine, to the chamber —18— within the piston —12— and nipple —13—. A rotary valve —19— controls the communication of the pipe —17— with the chamber —18— said valve being within the valve casing —15—, as best indicated in Figure 11. The operation of the valve —19— is controlled by means of a bi-partite lever —20— which has its end journaled on the valve —19— and its opposite end pivotally connected to the float —6—, the float being provided with a pair of spaced, upwardly projecting bars —21— for this purpose. The operation of this construction is, that as the float moves up and down it carries with it the lever —20—, the ends of the lever mounted on the valve —19— being free to rotate with respect to the valve. For the purpose of causing rotary movement of the valve at pre-determined positions of the float, the spring —22— is provided having one of its ends mounted in the slot —23— formed in the end of the valve —19— and having its intermediate portion wound about the end of the valve, with the opposite end of the spring connected to a pin —24— extending outwardly from one section of the bi-partite lever —20—.

It will be seen with this construction, that as the lever —20— moves up and down, the spring —22— tends to rotate the valve —19— in the direction of movement of the lever —20—. In order to prevent gradual opening and closing of valve, and to effect a sudden snap-over action of the same to its position where communication is made with the pipe —17— and then suddenly to a position where such communication is cut off and communication with the atmosphere effected, one of the sections of the bi-partite lever —20—, as best shown in Figure 5, is provided with a cam member —26— at the end journaled upon the valve —19— adapted upon rotation of the lever —20— by means of rise and fall of float —6— to engage pins —27— upon the respective dogs or ratchets —28— that engage with the cam —29— that is rigidly mounted on an intermediate portion of the valve —19—.

The cam —29— is so formed that it has a pair of ratchets or projections —30— spaced apart a distance sufficient to determine the two positions of the valve —19—, the one position when the suction port is open and the other position when the atmospheric port —31— as best shown in Figure 2, is open.

The spring-actuated dogs —28— engage their respective projections or ratchets to prevent rotation of the valve when the lever —20— is moved either up or downwardly, by corresponding movement of the float until sufficient rotation of the lever —20— has been had so that the cam —26— moves the respective dog from engagement with its ratchet to permit rotation of the valve by means of spring —22—. When the cam has moved the dog from engagement with the ratchet, the spring —22— suddenly snaps the valve to a reverse position, either opening the atmosphere port and closing the suction port, or opening the suction port and closing the atmosphere port dependent upon the direction of movement of lever —20—. The upper end —10— of the float is provided with a recess —32— in one side adapted when the piston —12— is moved downwardly by suction produced in chamber —18— to form a communicating passage through disk —11— permitting the suction or vacuum to be transferred to chamber —2—. Downward movement of piston —12— permits closing of the valve —8— by gravity, and further downward movement of the piston is permitted, due to the loose connection between the lower portion of the float stem and the part —10— until such last motion is taken up, when the piston —12— holds the valve —8— rigidly in closed position. At that time the recess or channel —32— affords communication between the chamber —18— and the chamber —2— so that the vacuum passes into the chamber —2— to elevate liquid in the said chamber through the nipple —5—. This condition of vacuum is maintained until such time as the float is moved upwardly to a position where the cam —26— moves the required pawl —27— from engagement with its respective ratchet —30— and spring —22— then snaps the valve to reverse position closing the suction connection and opening the air vent —31—.

The production of atmospheric pressure in the chamber —2— permits the spring —14— to raise piston —12—, opening valve —8—, and the liquid flows by gravity from chamber —2— to chamber —3—. This operation is repeated in accordance with the requirements of the carburetor or other device being fed.

As best illustrated in Figure 11, the valve casing —15— has two channels extending therethrough, viz: the atmospheric vent —31— and the suction channel —16— and the valve has, in like manner, two conduits

therethrough which are adapted to be brought into registration and moved out of registration with respective conduits --31-- and --16-- to effect the communication 5 above described.

It will be obvious that other snap-over mechanisms may be provided which will be capable of effecting this sudden movement of the valve --19-- at the time required, 10 and it may be that a gradual movement of these valves is sufficiently effective for the purpose at hand, although the structure described is preferable.

In Figure 12 a slightly different construction is shown, in that the piston --33-- corresponding to the piston --12-- is arranged within the upper chamber --2--, and within the valve casing --34-- which contains a rotary valve --35-- of the same construction as the valve --19--, adapted to be operated by a float --36-- and lever --37-- corresponding to the lever --20--. The snap-over mechanism is of the same construction as that described in the other figures. In this construction shown in Figure 12, the valve --38-- is mounted loosely upon a stem --39-- with an interposed spring --40-- adapted to extend the valve and stem to their limit of relative movement. The upper end of this stem is connected to the piston --33-- and extends through disk --41-- and is normally held in its upper limited movement by spring --42-- interposed between the disk and the piston in like manner, as heretofore described. The suction applied through the conduit as illustrated in Figure 12 moves the piston downwardly and closes valve --38--, the lost motion connection between the stem and the valve permitting some relative movement and a continued movement of piston --33-- after the valve has closed.

The surface area of the piston --33-- should be somewhat greater than the surface area of the valve --38-- in like manner as the surface area of the piston --12-- should be somewhat greater than that of the valve --8-- in order that the vacuum will at all times maintain the valve positively in closed position. The same atmospheric vent is provided in connection with Figure 12 as that illustrated in Figure 11, and the valve --35-- is of the same form and construction as the valve --19-- for operation in connection with the suction and air conduits as above described.

The valve stem --39-- is in like manner, as valve stem --7--, provided with a recess --43-- which forms a means of communication between the piston chamber --44-- and chamber --45-- of the tank to effect communication between the source of suction and the chamber --45-- at the desired time and with the desired position of the parts.

Although I have shown and described

specific constructions as illustrative of perhaps preferred embodiments of my invention, I do not desire to limit myself to the details of construction, form or arrangement of the apparatus, as various changes 70 and modifications may be made in the same without departing from the appended claims.

I claim:

1. In a device of the class described, an 75 upper chamber and a lower chamber, and means of communication between the said chambers, a valve controlling said communication, and suction-actuated means having a loose connection with said valve for holding 80 the same to its seat.

2. In a device of the class described, an upper chamber and a lower chamber, and means of communication between said chambers, a valve controlling said communication, a valve stem connected to said valve, and suction-actuated means for moving said valve stem to close the valve. 85

3. In a device of the class described, an upper chamber and a lower chamber, means 90 of communication between said chambers, a valve controlling said communication, a valve stem connected to said valve, suction-actuated means for moving said valve stem to close the valve, and spring means for 95 reversely actuating said valve stem to open the valve.

4. In a device of the class described, a chamber for the reception of liquid, a piston chamber, a piston movable in said chamber, means for producing vacuum in said piston chamber, means actuated by the production of vacuum therein for effecting communication between the piston chamber and the liquid-receiving chamber, and spring 105 means for moving said piston in one direction.

5. In a device of the class described, a chamber for the reception of liquid, a piston chamber, a piston movable in said chamber, 110 means for producing vacuum in said piston chamber, means actuated by the production of vacuum therein for effecting a communication between the piston chamber and the liquid-receiving chamber, spring 115 means for moving said piston in one direction, a valve controlling communication of the vacuum-producing means with said piston chamber, and float actuated means for controlling said valve. 120

6. In a device of the class described, an upper chamber and a lower chamber, a float in the upper chamber, a float stem, a valve mounted on the float stem and controlling the communication between said chambers, 125 a piston connected to said stem and suction means for actuating said piston to close said valve.

7. In a device of the class described, a liquid-receiving chamber, an auxiliary cham- 130

- ber in communication therewith, a valve controlling said communication, a valve stem connected to the valve, a piston connected to the valve stem, suction means for actuating the piston to close said valve, and means for bringing said suction means into communication with the liquid-receiving chamber when said valve is closed.
8. In a device of the class described, a liquid-receiving chamber, an auxiliary chamber in communication therewith, a valve controlling said communication, a valve stem connected to the valve, a piston connected to the valve stem, suction means for actuating the piston to close said valve, means for bringing said suction means into communication with the liquid-receiving chamber when said valve is closed, and float-actuated means controlling the suction means and for bringing the said liquid receiving chamber into communication with the atmosphere.
9. In a device of the class described, an upper chamber and lower chamber, means of communication between said chambers, a valve controlling said means of communication, and a piston having a loose connection with said valve for actuating the same.
10. In a device of the class described, an upper chamber and a lower chamber, means of communication between said chambers, a valve controlling said communication, a piston chamber, a piston in said chamber, a stem connecting said piston with said valve, a suction connection to said piston chamber, and means for bringing said piston chamber into communication with said upper chamber when vacuum has been produced in the piston chamber.

In witness whereof I have hereunto set my hand this 24th day of June 1921.

WILLIAM SPARKS.
